UNITED STATES PATENT OFFICE.

EARL F. COLLINS, OF CHARLESTON, WEST VIRGINIA.

DESIGN FOR AN IDENTIFICATION SIGN FOR OPTOMETRISTS.

Application filed July 30, 1920. Serial No. 400,250. Term of patent 3½ years.

To all whom it may concern:

Be it known that I, EARL F. COLLINS, a citizen of the United States, residing at Charleston, in the county of Kanawha and State of West Virginia, have invented a new, original, and ornamental Design for Identification Signs for Optometrists.

The figure is a plan view of a sign, showing my new design.

I claim:

The ornamental design for an identification sign for optometrists as shown.

EARL F. COLLINS.
